UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

ELECTRICAL APPARATUS.

Application filed February 17, 1923. Serial No. 619,615.

This invention relates to a new and improved electrical apparatus, particularly adapted for translating sound waves into X-rays or variations of X-rays which can be efficiently photographed or reproduced upon a film, thereby constituting a translatable film record of sound waves, particularly articulate or musical sound waves.

The invention centers especially about the utilization of an apparatus for producing X-rays as an apparatus for translating sound wave variations into X-ray variations, which may be photographed for the purpose of producing a translatable record of sound wave variations.

Other objects and advantages relate to the details of the apparatus, all as will more fully appear from the following description, taken in connection with the accompanying drawings, in which:—

The figures diagrammatically illustrate embodiments of my invention.

The apparatus, as shown in Figure 1, comprises a microphone —1— connected in circuit with a source of potential, as battery —2—, and the primary —3— of a transformer —4—, the secondary —5— of which is connected in circuit with the filament —6— and grid —7— of an electron-discharge device —8—, the plate —9— of which is connected through a source of potential, as battery —10— with the grid —11— disposed within the bulb —12— of the X-ray tube.

The filament —6— may be heated in any suitable manner as by the heating circuit, including a source of potential, as battery —13—. This type of X-ray tube embodies a filament —14— adapted to be heated in any suitable manner, as by heating circuit including a source of potential, as battery —15—, the filament —14— being connected in circuit with an anode —16— illustrated in the form of a plate, such circuit including a source of potential, as battery —17—.

The X-ray tube operates in the usual manner by bombardment of the anode —16— by the cathode rays given off by the heated filament —14—, the X-rays emanating from the plate or anode —16— as a result of such bombardment.

The intensity of such bombardment in the apparatus here disclosed is varied in accordance with sound wave variations which effect

variations in the potential of the grid —11—, which is preferably positioned, as shown, intermediate the filament —14— and plate —16— so as to effect the intensity of the X-rays emanating from the plate. These rays may be photographed in any suitable manner by any suitable apparatus which may, perhaps, preferably embody a film —19— moving across the small slit —20—. This slit may preferably be formed in a lead screen that to a maximum degree prevents the passage of the rays therethrough or the X-ray tube may in any suitable and well known manner, be screened by such a plate of lead.

In Figure 2 a somewhat different form of apparatus is illustrated in that the electrical variations, as produced by sound wave variations, are not brought in upon an electrode such as the grid —11—, but on the other hand, the circuit connecting the filament —14— and the plate —16— of the X-ray tube includes the secondary —21— of a transformer —22—, the primary —23— of which is connected in circuit with the filament —6— and plate —9— of the electron-discharge device —8—. In this manner, the electrical variations as effected by sound wave variations are applied directly to the filament plate circuit of the X-ray tube to effect in a similar manner the intensity of the X-rays emanating from the plate —16—.

In Figure 3 a further embodiment of my invention is illustrated in that the filament —14— and the plates —16— of the X-ray tubes are connected directly in the circuit between the filament —6— and plate —9— of the electron-discharge device —8— and the transformer —22— is entirely omitted.

In each of these apparatus, however, the X-rays emanating from the plate —16— are varied in intensity in accordance with electrical variations caused by sound wave variations, and a photographic record of the X-rays emanating from the plate —2— is in effect a re-translatable record of sound wave variations. The plate —16— in the usual manner should be formed of some material capable of withstanding the bombardment of cathode rays given off by the filament without material deterioration.

Battery —17— may be replaced by a generator to supply very high voltages or any known source capable of supplying the right

current and voltage for the production of either soft or hard X-rays.

Altho I have shown and described specific structures as illustrative of embodiments of my invention, I do not desire to limit myself to the details of form, construction or arrangement of the parts, as various changes may be made in each without departing from the invention, as set forth in 10 the appended claims.

I claim:

1. The combination with means for producing X-rays, of means for varying said rays in accordance with sound wave variations.

2. The combination with means for producing X-rays, of means for varying said rays in accordance with sound wave variations, and means for photographing the 20 X-rays as varied.

3. The combination with an electric circuit, of means for varying said circuit in accordance with sound waves, means for amplifying such variations, means for producing X-rays, and means for varying the production of said X-rays in accordance with such amplified variations.

4. The combination with an electric circuit, of means for varying said circuit in 30 accordance with sound waves, means for amplifying such variations, means for producing X-rays, means for varying the pro-

duction of said X-rays in accordance with such amplified variations, and means for photographing the X-rays as varied.

5. The combination with means for producing X-rays, of means for varying the intensity of said rays in accordance with sound wave variations.

6. The combination with means for producing X-rays, of means for varying the intensity of said rays in accordance with sound wave variations, and means for photographing the X-rays as varied.

7. In an apparatus of the class described, means for producing X-rays including a bulb containing a pair of spaced electrodes, one of which is adapted to be heated, means for heating the heatable electrode, and means for varying the intensity of the X-rays in accordance with sound wave variations.

8. In an apparatus of the class described, means for producing X-rays including a bulb containing a pair of spaced electrodes, one of which is adapted to be heated, means for heating the heatable electrode, means for varying the intensity of the X-rays in accordance with sound wave variations, and means for photographing the X-rays as varied.

In witness whereof I have hereunto set my hand this 1 day of February 1923.

THEODORE WILLARD CASE.
